United States Patent Office

Des. 205,570
Patented August 16, 1966

205,570

COMBINED ROTISSERIE AND HOT AIR ENGINE

Orville Z. Frazier, 732 Sherman SE., Grand Rapids, Mich.

Filed June 23, 1965, Ser. No. 85,863

Term of patent 14 years

(Cl. D81—10)

FIG. 1

FIG. 2

BY

FIG. 3

FIG. 4

FIG. 1 is a perspective view taken from the front of the combined rotisserie and hot air engine, showing my new design; and

FIG. 2 is a perspective view taken from the front and one end thereof, a support being broken away for the convenience of illustration only;

FIG. 3 is a side elevational view thereof; and,

FIG. 4 is a rear elevational view thereof.

I claim:

The ornamental design for a combined rotisserie and hot air engine, substantially as shown and described.
